UNITED STATES PATENT OFFICE.

WARREN B. WHITE, OF ABINGTON, MASSACHUSETTS.

PROCESS OF MAKING BOOTS OR SHOES.

Application filed July 12, 1923. Serial No. 651,173.

To all whom it may concern:

Be it known that I, WARREN B. WHITE, a citizen of the United States, and resident of Abington, in the county of Plymouth and 5 State of Massachusetts, have invented an Improvement in Processes of Making Boots or Shoes, of which the following description, in connection with the accompanying drawings, is a specification, like letters on the 10 drawings representing like parts.

My present invention is an improved boot or shoe and a novel process of making the same.

In my development of the art of improving the manufacture of boots and shoes, such 15 for example as that illustrated in my prior and copending applications, Ser. No. 511,590, filed Oct. 31, 1921, and Ser. No. 562,097, filed May 19, 1922, I have devised novel and 20 efficient means for manufacturing extremely flexible and tackless footwear. My present invention is a further improvement in the manufacture of a single soled tackless shoe resulting, substantially, in a welt type of 25 shoe, which, however, is equipped with a single sole, and which utilizes a removable insole during the process of manufacture. I believe that my present process and the resulting shoe so made, constitute distinct 30 novelties in the art of manufacturing boots and shoes, and I wish to claim both these features broadly herein.

In carrying out my invention, the upper materials, welt and outsole, are of usual 35 construction, and I prepare a special form of insole, similar in form and function to that illustrated in my prior applications above identified. Assembling the upper materials and prepared insole on a last, I then 40 last the shoe, and apply to the outside of the lasted shoe a suitable form, substantially a duplicate of the insole in contour, but preferably of reduced or smaller area. This form is temporarily secured to the insole in any 45 desired manner. Thereupon I draw the last, and apply a welt, stitching the welt through and through to the upper only, and utilizing the insole-like form as a guide for the inseam stitching machine to perform this 50 welt stitching. This welt stitching furthermore is preferably applied entirely beyond or outside of the marginal edge of the first insole on which the upper is lasted, said insole being preferably of less area, but substantially parallel in contour to the bottom 55 of the last. Thus the inseam stitching, at-

taching the welt, is connected to the upper only and not to the insole. This latter is intended to be removable. With the welt thus stitched, I then relast the shoe, apply 60 the outsole, and stitch the outsole to the welt in the usual manner, apply the heel, and finish and complete the shoe, performing the final operations in the same manner as 65 welt shoe work. The shoe is completed and I then remove the last and thereupon pull the first insole member, thus removing it and the lasting tacks carried by it, with the result that a single soled welt shoe, with the 70 inner margin of the welt secured to the upper and lining only by through and through stitching, and the welt and outsole secured by usual Goodyear welt stitching, is produced.

Instead of utilizing a removable form on 75 the bottom after it is lasted, it is possible and feasible to employ a fairly heavy removable insole of strong stock, which can be used repeatedly, and which is of sufficient 80 thickness and reduced or less area than the last bottom, so that this insole itself can be employed as the guide for the welt inseamming machine. In this case it is not necessary to use the second form above described, 85 which is applied after the shoes is otherwise lasted.

Referring to the drawings, illustrating a preferred embodiment of the invention,

Fig. 1 is a side view, partly in cross-section, illustrating the completed shoe, 90 made according to my process;

Fig. 2 is a cross-sectional view illustrating the shoe in lasted position;

Fig. 3 is a cross-sectional view showing the welt stitched to the upper outside the 95 insole;

Fig. 4 shows the completed shoe.

As shown in the drawings, upper materials 1, comprising a shoe upper and a lining of any suitable style, desired shape or form 100 are employed. The upper 1 is assembled on a last 2 and a specially prepared insole 3 is applied to the last bottom. This insole is intended to be removable and carries a plurality of lasting points, tacks or instrumentalities designated as 4, these being preferably of the type illustrated in my said prior cases. This temporary insole member 3 is of smaller area, although substantially parallel in contour to the bottom of the last, 105 but leaves a considerable margin, indicated a 5, 5, at either side, to enable the welt stitch-

ing to be attached free of this insole. The upper is lasted according to my process already covered by said pending applications, and thereupon the last 2 is withdrawn and 5 a welt 6 is applied and stitched by inseam stitching 7, see Fig. 3. I may desire to last and permanently tack the toe and heel portion on small insole sections 8 and 9, as is customary, but the main portion of the 10 forepart and shank of the shoe, where flexibility is desired, employ the construction illustrated in Figs. 2 and 3.

In applying the welt 6 and attaching the same with the stitching 7, two methods may 15 be employed. Where the insole stock 3 is heavy and thickened, and with the last removed, I may use the edge of the same, 9, as a guide for the inseam stitching machine, which may be a straight through and through 20 needle machine, similar to that employed for various operations in shoe factories. This is readily accomplished by depressing the thin flexible upper and lining over the edge 9 in the steps indicated at 5, Fig. 2, 25 which with the last removed, is easily done and the inseam stitching readily applied. Or I may apply to the lasted upper a removable form indicated at 10 in Fig. 3. This form can be secured to the insole 3 by 30 one or two tacks if desired, and constitute simply an edge guide or form to maintain the stitching machine setting the stitches 7 into position and alinement. Thereupon the form 10 is removed and the shoe relasted. 35 As thus relasted, the outsole 12 is then applied and the outsole stitching 14 is set, uniting the outsole and welt 6 in the usual welt shoe construction; the heel applied, edges trimmed, burnished, and the shoe completed and finished, whereupon the last is 40 withdrawn and the removable insole 3 pulled out, carrying the lasting members 4 and leaving a single soled tackless welt shoe. If desired a sock lining 15 can be fitted with 45 in the shoe, as is customary. My process thus includes simple, novel and efficient methods of forming a shoe, utilizing through and through stitching to unite the upper and welt entirely free of the insole, 50 employing my novel type of insole and lasting devices, eliminating the necessity for filling, trimming the upper or the like, and presenting the appearance of an extensive Goodyear welt shoe, while comprising the 55 characteristic flexibility and comfort of a turn shoe. An important advantage of this novel shoe thus constructed is that it is entirely free from tacks, has great flexibility and furthermore, although a single soled 60 shoe, yet it can be repaired, as long as the welt 6 is intact, in an identically similar

manner to the methods employed in repairing welt shoes.

My invention is further described and defined in the form of claims as follows:

1. The improvement in the art of manufacturing boots and shoes, which consists in providing a removable insole, of less area than the bottom of the last on which it is used, assembling the upper and said insole on a last, lasting the upper, removing the last, stitching the upper only around the margin of the forepart and shank to a welt by through and through stitching, applying an outsole and attaching the same to said welt, removing the last and withdrawing the insole from the inside of the shoe. 70

2. The improvement in the art of manufacturing boots and shoes, which consists in providing a removable insole of less area than the bottom of the last on which it is used, said insole carrying lasting devices, assembling the upper and said insole on a last, lasting the upper, removing the last, stitching the upper only around the margin of the forepart and shank to a welt by through and through stitching, applying an outsole and the attaching same to said welt, removing the last and withdrawing the insole and said lasting devices from the inside of the shoe. 80

3. The improvement in the art of manufacturing boots and shoes, which consists in providing a removable insole, of less area than the bottom of the last on which it is used, assembling the upper and said insole on a last, lasting the upper, applying a removable form on the bottom of the lasted upper and insole, substantially co-extensive with the insole, removing the last, 90 stitching the upper only around the margin of the forepart and shank to a welt by through and through stitching, utilizing said form as a guide for the stitching machine, applying an outsole and attaching the 100 same to said welt. 105

4. The improvement in the art of manufacturing boots and shoes, which consists in assembling an insole and upper materials on a last, lasting the upper to said insole, temporarily securing a removable form on the bottom of the lasted upper and insole, utilizing the marginal edge of said form as a guide for a through and through stitching machine, applying a welt and attaching the 110 same by a through and through stitching machine, guiding it on said form around forepart and shank, removing the form, and attaching an outsole to the welt. 115

In testimony whereof, I have signed my 120 name to this specification.

WARREN B. WHITE.
